UNITED STATES PATENT OFFICE

124,676

DESIGN FOR A NOZZLE HOLDER

Elwood E. Hansen, Elkhart, Ind., assignor to Elkhart Brass Mfg. Co., a corporation of Indiana

Application November 2, 1940, Serial No. 96,262

Term of patent 14 years

To all whom it may concern:

Be it known that I, Elwood E. Hansen, a citizen of the United States, residing at Elkhart, in the county of Elkhart and State of Indiana, have invented a new, original, and ornamental Design for a Nozzle Holder, of which the following is a specification, reference being had to the accompanying drawing, forming a part thereof, in which:

Fig. 1 is a view in front elevation of a nozzle holder showing my new design; Fig. 2 is a view in side elevation thereof; Fig. 3 is a top plan view thereof; and Fig. 4 is a bottom plan view thereof.

I claim:

The ornamental design for a nozzle holder, as shown.

ELWOOD E. HANSEN.
